UNITED STATES PATENT OFFICE.

VIRGIL P. ADAMS, OF BREMERTON, WASHINGTON.

SERVING-MACHINE.

1,392,611.

Specification of Letters Patent.

Patented Oct. 4, 1921.

Application filed September 9, 1920. Serial No. 409,185.

To all whom it may concern:

Be it known that I, VIRGIL P. ADAMS, a citizen of the United States, residing at Bremerton, in the county of Kitsap and State of Washington, have invented certain new and useful Improvements in Serving-Machines, of which the following is a specification, reference being had to the accompanying drawings.

10 This invention relates to an improved serving machine, and an object is to provide a simple, efficient and fast apparatus for serving or binding around or nearly around the cylindrical material, such as rope, wire, 15 pipe or hose or the like with marline, rope, twine, wire or other suitable material, such as tape or the like.

Another object is to provide a machine of this kind wherein means is afforded for 20 insuring the winding of the strands of material close and tight and in a smooth manner about the material served.

Still another object is to provide a machine to be suspended upon the material or 25 rope, hose or other cylindrical strands, including means for tensioning the material to be served, so that it can be tightly and closely wound with the serving material.

A further object affords means whereby 30 the serving material may be considerably tensioned as it is being unreeled and served on the material to be wound or wrapped, so that the convolutions may be engaged tight and close so as to thoroughly bind the material being served.

A still further object consists in the provision of means so arranged relative to the serving material so as not only to hug close to the material being wound and close to 40 the serving material, also advancing in front of the serving material to keep it closely bound and providing means for advancing the entire machine along the material being served.

45 Additionally, the invention aims to provide means for making quick adjustments for different sizes of rope or other material to be served.

While the design and construction at 50 present illustrated and set forth is deemed preferable, it is obvious that as a result of a reduction of the invention to a more practical form for commercial purposes, the invention may be susceptible of changes, and

the right to these changes is claimed, provided they are comprehended within the scope of what is claimed. 55

The invention comprises further features and combination of parts, as will be herein-after set forth, shown in the drawings and 60 claimed.

In the drawings:—

Figure 1 is a view of the serving machine showing parts in elevation and showing certain other parts in section and illustrating 65 the machine as suspended upon a cable, rope or other material being served.

Fig. 2 is a view of one end of the machine showing certain of the bearings for the sleeves 60 and the sleeves in section and also 70 illustrating the machine as suspended on the cable or rope being served.

Fig. 3 is a view in elevation of the opposite end of the serving machine more clearly showing other features of the invention. 75

Referring more especially to the drawings, 1 designates a frame which may be of any suitable shape or configuration, preferably of the construction shown, and arranged vertically and adapted to suspend 80 from the rope or other material being served. Fastened by suitable bolts 2 to the lower part of the frame is the frame 3 of a conventional form of electric motor 4. The shaft 5 of the motor carries a sprocket 6 85 around which a sprocket chain 7 operatively engages. Projecting from approximately the central portion of the frame 1 are suitable bearings 8 in which a shaft 9 is mounted. Feathered or keyed to one end of the 90 shaft, as at 10, is a sprocket 11 upon which the chain 7 travels. Fixed to the other end of the shaft 9 is a pinion 12.

The frame 1 adjacent the bearings 8 is provided with a projecting arm 13 and 95 bolted thereto, as at 14, is a clamp 15. This clamp comprises the base section 16 and the movable clamping section 17. The two sections are hingedly united, as at 18. These sections are semi-cylindrical in cross section 100 and projecting from one end of the base section is a projection 19. Projecting from the corresponding end of the clamping section is a bifurcated projection 20. Pivoted to the projection 19, as at 21, is a screw 22 105 designed to swing into engagement with the bifurcation 23 of the projection 20, there being a wing nut 24 to be screwed home in

engagement with the projection 20 to hold the clamping section rigid relatively to the base section of the clamp.

This clamp affords a bearing 25 for a revoluble cylinder 26 when serving the rope or the like. One end of the cylinder has a flange 27 to which an interior radial flange 28 of a spur gear ring 29 is secured by screw bolts 30. This spur gear ring meshes with 10 the pinion 12 so that when power is transmitted from the electric motor to the shaft 9 through the medium of the sprocket gears 6 and 11 and the chain 7, motion will be imparted to the cylinder 26. The spur gear 15 comprises two sections corresponding to and are carried by the respective sections of the cylinder 26.

The upper part of the frame 1 beyond the bearings 8 is provided with an overhanging 20 arm 31 in which a screw 32 is swivelly mounted. This screw on its upper end is provided with a crank handle 33. The lower end of the screw threads through a U-shaped bracket 34 which is guided vertically relatively to the upper part of the frame 1. In order that the bracket 34 may be guided, a boss 35 projects from one arm of the bracket 34 and into a slot 36 of the frame. The boss 35 has a projecting screw lug 37 to which a 25 nut 38 and washer 39 are applied. The boss 35 projects slightly less than the thickness of the frame 31, so that when tightening the nut 38, the frame 34 will be locked, and when loosened, the frame 34 is free for adjustment. Projecting transversely of the 30 arms of the bracket 34 is a headed pin 40, the head of which is countersunk in one of the arms of the bracket while the other end of the pin receives a cotter key 41, thereby holding the pin 40 in position. This pin 40 constitutes a journal for the trolley wheel 42 which operates upon the rope, cable or other material being served, thereby acting to suspend the serving machine. It will be noted 45 that by operating the crank handle 33, the U-shaped bracket 34 may be moved vertically for the purpose of adjusting the trolley wheel relatively to the overhanging arm 31 of the frame 1 in order to tension the 50 rope, cable or other material being served, and insure centering the cable or other material with respect to the cylinder 26, as the serving material is wound or wrapped on the cable.

55 The frame 1 has bolted thereto, as at 43 and 44, a suitable handle 45 by which the machine may be moved along the material being served and transporting the machine from place to place when such operation is 60 necessary. However, the machine, as it is serving the rope or cable, is automatically advanced along the rope or cable as the same is being served.

The cylinder, like the clamp, also consists 65 of two sections 46 and 47 which are hingedly

united, as at 48, and diametrically opposite the hinge connections 48 are the projecting arms 49 and 50. A screw 51 is pivoted to the arm 49 and adapted to move into engagement with a bifurcation 52 of the arm 50, 70 there being a wing nut 53 on the screw and adapted to clamp against the arm 50 to hold the two sections of the cylinder together. Where the two sections of the cylinder engage, at diametrically opposite points very 75 close to the inner cylindrical surface of the cylinder, interengaging shoulders 54 are provided to hold the two sections of the cylinder in registration. Also the cylinder is provided on its exterior with an annular 80 enlargement 55 to operate in the bearing 25 of the clamp, thereby preventing axial movement of the cylinder, especially owing to the annular flanges 56 of the two sections of the clamp. 85

The end of the cylinder opposite the spur gear ring is provided with segmental projecting flanges 57 to which the clamping plates 58 are bolted, as at 59. These clamping plates have bearings in which the sleeves 60 are guided. The sleeves 60 have forks 61 and between the forks of three of the sleeves tightening or binding rollers 62 are journaled while between the forks of the other sleeve a combined binding and feeding roller 63 is journaled. This roller 63 is distinguished from the other rollers owing to the same having an annular flange 64 which co-operates with the strands of the serving material so as to not only force or 100 tighten the convolutions of the serving material together as it is being fed or let out on the material being served but also acts to advance the machine along the cable or rope being served. In projecting bearings 65 105 carried by the segmental flanges 57 screws 66 are swivelly mounted, as at 67. These screws are threaded into the sleeves 60 so that by moving the screws in one direction or the other, the rollers carried by the sleeves 110 may be moved radially toward and from the rope, cable or other material being served in order to increase or decrease the tensioning of the serving material as it is wound or wrapped upon the cable or rope being 115 served and locating the cylinder 26 centrally on various sizes of material to be served.

The lower section of the cylinder 26 is provided with guide sheaves 68 and 69 over which the serving material passes and is 120 tensioned as it leaves its reel in order to guide the serving material over the advancing roller 63.

Projecting outwardly in opposite directions and downwardly from the lower section of the cylinder 26 are bearing arms 70 and 71 affording means for the support of a reel 72 which is designed to carry the serving material. A friction washer 73 is arranged adjacent the bearing of the arm 70 130

and is partially countersunk in one of the heads of the reel, axially concentric with the hub 74 of the reel. The friction washer also has an annular flange 75 which extends into

5 one of the heads of the reel. A suitable screw stud 76 is threaded through the bearing of the arm 70 and into the flanged portion of the friction washer 73, thereby rotatably supporting one end of the reel. A lock 10 nut 77 engages the screw stud 76 and locks the same in the bearing of the arm 70.

The arm 71 has a lateral portion 78 terminating in a depending part 79 in a bearing of which a screw 80 is mounted. The inner 15 end of the screw 80 is reduced, and pinned at 81 to the reduced portion 82 is a friction washer 83 which is countersunk in the opposite head of the reel 72. A nut 84 is carried by the screw at a point between the friction 20 washer and the depending portion 79 of the arm 71. This nut is adjustable along the screw and interposed between the nut and the washer 85 is a coil spring 86. The washer 85 is disposed adjacent the depending 25 part 79 of the arm 71. The washer 85 is provided with notches for the reception of one end of said coil spring, so that the washer will remain substantially fixed relatively to the spring. A wing nut 30 87 is threaded upon the screw 80 and co-operates with the end of the bearing of the arm 71 so as to move the screw axially relatively to the reel for the purpose of increasing or decreasing the friction of the washer 83 in 35 its bearing of the reel head in order to increase or decrease the tension of the serving material relatively to the reel.

In operation, the cable or rope being served is strung taut, after which the machine is suspended upon the cable with the 40 cable or rope engaging the trolley wheel 42, after which the tension rollers 62 are adjusted relatively to the serving material wound upon the rope or cable being served. The machine-advancing roller 63 is then adjusted so that its flange will ride against the serving material, then the motor is started. Power is then transmitted from the motor to the shaft 9 and thence to the cylinder. The 45 serving material passes from the reel, first over the roller 68 and then over the roller 69 so that the serving material will pass about the material to be served in a position to be engaged by the machine-advancing 50 roller.

When power is transmitted to the shaft 9, power is in turn transmitted to the cylinder through the gear ring 29. As the cylinder 55 revolves and since the serving material is let out or guided upon the material being served by the rollers 68 and 69 carried by the cylinder, convolutions of the serving material are passed about the rope or cable being served. When the cylinder 60 receives revoluble movement, the reel 72 re-

volves therewith as also does the handle 88 which is mounted between the arms 89 of the upper section of the cylinder and secured in position by the nuts 90.

By turning the crank handle 33 in a direction to move the trolley wheel 42 toward the cable or rope being served, it is possible to adjust the machine relatively to the cable or rope being served in order to tension the serving material and to more readily guide 75 the serving material upon the cable or rope being served.

As previously stated, the flanged roller 63 is located in a position advancing in front of the serving material, thus not only keeping the material tightly and closely bound but also affording means for moving the entire machine along the cable or rope as it is served.

The invention having been set forth, what 85 is claimed as new and useful is:

1. In a serving machine, a frame movable longitudinally along the material being served, a mechanism bodily revoluble concentrically about and on a radius from the 90 material being served and carried by the frame and letting out the serving material, said mechanism including means extending radially of the mechanism for closely engaging the convolutions of the serving material 95 and at the same time advancing the machine along the material being served, and a trolley mechanism for suspending the frame on the material being served.

2. In a serving machine, a frame movable 100 longitudinally along the material being served, a mechanism bodily revoluble concentrically about and on a radius from the material being served and carried by the frame and letting out the serving material, said 105 mechanism including means extending radially of the material being served for closely engaging the convolutions of the serving material and at the same time advancing the machine along the material being served, a 110 trolley mechanism for suspending the frame on the material being served, and means for adjusting the trolley mechanism for adjusting the frame relatively to the material being served.

3. In a serving machine, a frame for movement longitudinally on material to be served, a revoluble mechanism carrying a reel for serving material, said mechanism including a revoluble cylinder, means carried by the frame for revolubly supporting said cylinder, means carried by the frame and operatively connected with the cylinder for imparting power thereto, said cylinder having means at one end for paying out the 125 serving material, a device operatively engaging the advanced convolutions of the serving material for forcing the convolutions close together and at the same time advancing the machine along the material being 130

served, said cylinder having means for tensioning the serving material and forcing it radially toward the material being served.

4. In a serving machine, a frame adapted for suspension from a strand to be served and carrying driving means, a serving mechanism revoluble concentrically about and on a radius from the strand, said mechanism including a revoluble cylinder concentric with the strand, means operatively connecting the cylinder and the driving means, devices disposed radially of and carried by the cylinder and having means for forcing the convolutions of the serving material close together on the strand being served and acting to advance the mechanism along the material being served, said devices acting to support one end of the mechanism and the frame, and a trolley wheel carried by the frame and engaging the served portion of the strand to support the frame and the other end of the mechanism.

5. In a serving machine, a frame adapted for suspension from a strand to be served and carrying driving means, a serving mechanism revoluble concentrically about and on a radius from the strand, said mechanism including a revoluble cylinder concentric with the strand, means operatively connecting the cylinder and the driving means, devices disposed radially of and carried by the cylinder and having means for forcing the convolutions of the serving material close together on the strand being served and acting to advance the mechanism along the material being served, said devices acting to support one end of the mechanism and the frame, and a trolley wheel carried by the frame and engaging the served portion of the strand to support the frame and the other end of the mechanism, and means manually actuated for adjusting the trolley wheel to govern the equilibrium of the frame and the mechanism relatively to the strand.

6. In a serving machine, a frame adapted for suspension from a strand to be served, a serving mechanism carried by one end of the frame and provided with radially disposed devices being adjustable for increasing and decreasing the tension of the serving means and to maintain the mechanism concentrically with the strand, a trolley wheel carried by the other end of the frame and being adjustable toward the strand for holding the other end of the mechanism con-

centric with the strand, and driving means on the frame suspended from the strand and operatively connected to the mechanism and performing the double function of imparting movement to the mechanism and coöperating with said devices and the trolley wheel for balancing the frame and the mechanism on the strand.

7. In a serving machine, a serving mechanism including a revoluble cylinder through which the strand to be served passes, devices at one end of the cylinder adjustable toward the strand for increasing and decreasing the tension of the serving material as it is served and to support one end of the cylinder concentric with the strand, a frame including a clamp bearing in which the other end of the cylinder is rotatably mounted, rotating means on the frame being engaged with the served strand to coöperate with said devices to maintain the cylinder and its bearing concentric with the strand, and driving means carried by the frame and suspended from the strand and operatively connected to one end of the cylinder and performing the double function of imparting movement to the cylinder and coöperating with the rotatable means for balancing the frame relatively to the cylinder.

8. In a serving machine, a serving mechanism including a cylinder having means at one end for engaging a strand being served, hangers depending from the cylinder, a reel interposed between the hangers and carrying the serving material, means coöperating and disposed axially with the reel for retarding the reel in its unreeling movement, and being adjustable to increase or decrease the retarding action, a rotating device engageable with the upper part of the served strand and coöperating with the first means for maintaining the cylinder concentric with the strand, a frame suspended from the cylinder and the rotating means, and driving means on the frame and suspended from the strand being operatively connected to the cylinder, for performing the double purpose of imparting movement to the cylinder and counterbalancing the frame and the serving mechanism on the strand, during the revoluble movement of the cylinder with the reel suspended therefrom.

In testimony whereof I hereunto affix my signature.

VIRGIL P. ADAMS.
